UNITED STATES PATENT OFFICE

GEORGE P. ITTIG, OF BRIDGEPORT, CONNECTICUT, ASSIGNOR TO BLACKSTONE SILVER COMPANY, INCORPORATED, OF BRIDGEPORT, CONNECTICUT, A CORPORATION OF CONNECTICUT

DESIGN FOR A METAL BORDER STRIP

Application filed December 14, 1929. Serial No. 33,790. Term of patent 3½ years.

To all whom it may concern:

Be it known that I, GEORGE P. ITTIG, a citizen of the United States, residing at Bridgeport, county of Fairfield, State of Connecticut, have invented a new, original, and ornamental Design for a Metal Border Strip, of which the following is a specification, reference being had to the accompanying drawing, forming part thereof.

Fig. 1 is a front view of a metal border strip showing my new design.

Figs. 2 and 3 are cross sections substantially on lines 2—2 and 3—3, respectively, of Fig. 1.

I claim:

The ornamental design for a metal border strip substantially as shown.

GEORGE P. ITTIG.
